H. F. HICKS.
PRESS.

No. 25,546.

Patented Sept. 20, 1859.

Inventor;

Horatio Francis Hicks.

UNITED STATES PATENT OFFICE.

HORATIO F. HICKS, OF GRAND VIEW, INDIANA, ASSIGNOR TO HICKS BROS.,
OF SAME PLACE.

IMPROVEMENT IN PRESSES.

Specification forming part of Letters Patent No. 25,546, dated September 20, 1859.

To all whom it may concern:

Be it known that I, HORATIO F. HICKS, of Grand View, Spencer county, Indiana, have invented certain new and useful Improvements in Presses for Hay, Cotton, &c.; and I do hereby declare the following to be a full, clear, and exact description of the same, reference being had to the accompanying drawings, making part of this specification.

The object of the said invention is to reduce friction in cotton-presses, hay-presses, &c., by means of stepped bearings and friction-rollers adapted to operate in connection therewith without tendency to displacement.

In the accompanying drawings, Figure 1 is a vertical section of a press embodying my improvement. Fig. 2 is a plan of the anti-friction frame. Fig. 3 is a perspective view of the same.

A is a common form of frame used to contain the hay, cotton, &c., to be pressed. It has firmly fitted in its ends the heads B B'. It may be supported as shown or suspended from joists, as most convenient. It is provided at the upper end with two doors, C, through which the press is charged and the material taken out when pressed. It has also an opening, D, at its lower end, through which the movable parts may be examined or removed and repaired.

E is the hoisting-platform or press-plate, to which the screw F is firmly secured, as shown.

G is the revolving nut, fitted to work in the screw F. At the lower end of the nut the arm H (to which the power necessary to work the press is applied) is securely connected.

I is a stationary collar or plate secured to the head B'.

K is the anti-friction frame or collar, which is devised to work between the collar or revolving nut G and stationary plate I.

K' are rollers journaled, as shown, in the frame K. The relative diameters of the ends of the rollers are proportioned to the circumference of the circle over which they are made to traverse, so that neither end may cause the other to drag and produce friction. The working-faces of nut G and collar I are stepped, as shown, so as to present horizontal bearings to both diameters of rollers K', by which means, whether such bearings be straight or slightly curved, no endwise pressure is imparted to the rollers.

I am aware that conical rollers have been interposed between the bearing-surfaces of presses for the purpose of reducing friction; but,

I claim as new and of my invention—

The described combination of stepped bearings G and I with rollers K', adapted to operate in connection therewith without endwise pressure or tendency to displacement, in the manner and for the purpose set forth.

In testimony of which invention I hereunto set my hand.

HORATIO FRANCIS HICKS.
